(57) **CLAIM**

The ornamental design for a handle for a cleaning article as shown and described.

DESCRIPTION

FIG. 1 is a top perspective view of a handle for a cleaning article showing my new design;

FIG. 2 is a bottom perspective view thereof;

FIG. 3 is a front elevational view thereof, the rear elevational view being a mirror image of FIG. 3;

FIG. 4 is a left side view thereof;

FIG. 5 is a right side view thereof;

FIG. 6 is a top plan view thereof;

FIG. 7 is a bottom plan view thereof;

FIG. 8 is a top perspective view of a handle for a cleaning article in a folding state; and,

FIG. 9 is a bottom perspective view thereof.

The broken lines in the figures are for the purposes of illustrating portions of the handle for a cleaning article, which form no part of the claimed design.

1 Claim, 6 Drawing Sheets
